UNITED STATES PATENT OFFICE.

LEO MANDELSTAMM, OF NEW YORK, N. Y.

DENTIFRICE.

No Drawing. Application filed October 28, 1924. Serial No. 746,417.

To all whom it may concern:

Be it known that I, LEO MANDELSTAMM, a citizen of the United States, residing at New York, in the county of New York and 5 State of New York, have invented certain new and useful Improvements in Dentifrices, of which the following is a specification.

My invention relates to improvements in dentifrices and more particularly to dentifrices containing radium.

An object of my invention is to provide a dentifrice which is harmless to the human organism but which is antiseptic and germicidal in nature and at the same time stimulating to the gums.

It is very easily possible to provide a dentifrice with the proper abrasive or cleansing ingredients but such a dentifrice in most cases has no germicidal action.

20 It is also easily possible to provide a dentifrice having a strong germicidal and antiseptic action but the difficulty in these cases is that such action is likely to have a detrimental effect upon the delicate tissues of the mouth.

I believe the improved dentifrice which I have devised combines the beneficial effects of the well-known dentifrices on the market which have no medicinal action, together 30 with the antiseptic and germicidal properties which are necessary in a dentifrice of most approved type.

My improved dentifrice is produced in the following manner:

35 As the base of my dentifrice, I use the following:—

2 ounces powdered chalk, 1 ounce powdered chloride of potash, 1 ounce of sugar, $\frac{1}{2}$ ounce water, $\frac{1}{2}$ ounce powdered 40 castile soap, 10 drops carbolic acid, 10 drops oil of cloves, 10 drops oil of cinnamon.

I claim no originality for the above ingredients as these are all ingredients well

known in dentifrices, but I have selected the ingredients in the above proportions as compatible with the additional substances which I propose to use in my improved dentifrice. 45

To 4 ounces of the above mixture as a base I add 4 centimeters of a 22% solution of vanadium chloride and 10 centimeters 50 of glycerin containing $\frac{1}{3}$ of a microgram of radium chloride. I find that radium chloride in a glycerin solution is stable and can be successfully used in combination with vanadium chloride of the above strength. 55

I have found by clinical tests that a dentifrice of the above composition whilst having the normal cleansing effect of the ordinary dentifrice, also provides by reason of its vanadium content a strong but harmless germicidal and antiseptic action. 60

The effect of the radium chloride present is to act as an invigorator and stimulant for the healthy and unhealthy gum tissue.

Having fully described the composition of 65 my improved dentifrice, what I claim is:—

1. In a dentifrice, the combination of neutral abrasive materials, a vanadium salt and a radium salt.

2. In a dentifrice, the combination of neutral cleansing and abrasive materials, and a vanadium salt. 70

3. In a dentifrice, the combination of chalk, essential oils, water, a vanadium salt and a radium salt. 75

4. In a dentifrice, the combination of chalk, oil of cloves, oil of cinnamon, a vanadium salt and a radium salt.

5. In a dentifrice, the combination of glycerin, neutral cleansing and abrasive materials and small amounts of vanadium and radium salts. 80

In testimony whereof I hereunto affix my signature.

LEO MANDELSTAMM.
